CLAIM

The ornamental design for a nightstand, as shown and described.

DESCRIPTION

FIG. 1 is a perspective view of a first embodiment of a nightstand showing our new design;

FIG. 2 is a top plan view thereof;

FIG. 3 is a front elevation view thereof;

FIG. 4 is a right side elevation view thereof, the left side being a mirror image of the right side;

FIG. 5 is an enlarged fragment of a portion of the nightstand shown in FIG. 1 and labeled 5;

FIG. 6 is an enlarged fragment of a portion of the nightstand shown in FIG. 1 and labeled 6;

FIG. 7 is a perspective view of a second embodiment of a nightstand showing our new design;

FIG. 8 is a top plan view thereof;

FIG. 9 is a front elevation view thereof;

FIG. 10 is a right side elevation view thereof, the left side being a mirror image of the right side;

FIG. 11 is an enlarged fragment of a portion of the nightstand shown in FIG. 7 and labeled 11; and,

FIG. 12 is an enlarged fragment of a portion of the nightstand shown in FIG. 7 and labeled 12.

The fragmentary showing of wood grain in FIGS. 1-4 and 7-10 and shown in detail in FIGS. 5, 6, 11, and 12 is understood to be repeated throughout the surfaces shown. The second embodiment is shown with symbolic break in FIGS. 7-9, and those portions of the article between the break lines form no part of the claimed design.
